Patented Oct. 9, 1917.

UNITED STATES PATENT OFFICE.

ANGELO PANASCI, OF WATERBURY, CONNECTICUT.

DISH-LIFTER.

1,242,465.

Specification of Letters Patent.

Patented Oct. 9, 1917.

Application filed November 6, 1914. Serial No. 870,640.

To all whom it may concern:

Be it known that I, ANGELO PANASCI, a citizen of the United States, and a resident of Waterbury, in the county of New Haven and State of Connecticut, have invented 5 certain new and useful Improvements in Dish-Lifters, which improvements are fully set forth in the following specification.

This invention relates to improvements in 10 devices of that class available for grasping and holding various articles, particularly shallow dishes, as plates, saucers and the like, such devices being well designated dish lifters.

15 The object of this invention is to provide a dish lifter which shall be simple and inexpensive as regards its construction; durable, efficient and reliable in practical service; convenient in its application to practical purposes; and which shall possess certain well-defined advantages over prior analogous constructions.

The invention consists in certain combinations, details and parts whereby, together 25 with the novel disposition and relative arrangement of said parts, the attainment of the foregoing object is rendered practicable, all of which will be hereinafter more specifically referred to and set forth in the 30 claim hereto appended.

The invention is clearly illustrated in the accompanying drawing, wherein—

Figure 1 is a plan view of a dish lifter embodying my said improvements.

35 Fig. 2 is a cross-section of same, along the dotted line $\alpha-\alpha$ of Fig. 1.

Fig. 3 is a view showing in elevation and detached one of the dish-grasping clips made use of.

40 Fig. 4 is a view showing a modification of the tie-member made use of for connecting the main arms of the device.

Having reference to the accompanying drawing, wherein similar reference numerals denote like parts throughout the several views, I, in a general sense and in carrying out my invention, make use of a pair of duly connected arms 2, 2', formed from wire of suitable gage, elastically controlled, and 45 either of which is movable relatively toward and away from the other, after the manner of a pair of tongs.

The arms 2, 2', preferably formed from wire, are connected together by a tie-member 55 5, preferably coiled as shown, and also

formed from wire. Said tie-member may be formed integral with the arms 2, 2', as clearly indicated in Fig. 4, or the opposite linear members thereof, as 3', 3'', may be telescopically conjoined, one, as 3', with the adjacent end-portion of its coöperating arm, as 2, and the other, as 3'', with the adjacent end-portion of its coöperating arm, as 2', all as clearly illustrated in Fig. 1.

The joint between either of the linear 65 members 3', 3'', may be rendered permanent by brazing, soldering, or otherwise, as found expedient in practice.

The formation of the tie-member 3 as a unit separate from the arms 2, 2', is resorted 70 to only when the gage or stiffness of the wire from which the said arms are formed is such as to necessitate the application, in practice, of needless and hence undesirable stress in the operation of moving or closing either of the arms aforesaid in the direction of the other, against the elastic resistance as mainly afforded by the tie-member 3; such tie-member, accordingly, being formed from wire of a gage suitably less 75 than the gage of the wire made use of in the formation of the arms 2, 2', respectively, all as will be clearly understood.

The arms aforesaid are provided, one, as 2, with a non-returned advance end-portion 4, and the other, as 2', with a similar advance end-portion 4', each of said advance end-portions being curved or bowed away from the other, and occupying a plane common thereto.

On one of said end-portions, as 4, I firmly fasten a plurality of dish-grasping clips, as 5, 5', while on the opposite end-portion, as 4', I also firmly fasten a plurality of like dish-grasping clips, as 4'', 5'', such of said 95 clips as are supported by either of the end-portions now under consideration, being suitably spaced apart therealong and each leading a suitable distance therefrom generally in the direction of such of said clips 100 as are supported by the end-portion arranged oppositely thereto, and generally in the direction of the longitudinal center-line of the device as a whole.

Each of the clips aforesaid affords, by 105 preference, dual prongs 6, 6', one overlying the other, though in some instances the same may advantageously afford a single prong only.

Said clips are preferably formed, each 110

from metal in the form of a flat strip, the same being bent or shaped upon itself for the formation of an eye 7, whereby the clip may be threaded, or otherwise conveniently positioned upon, the part which supports it, said clip being then permanently fastened to the part which supports it by brazing, soldering, or otherwise, as found expedient in practice.

10 For relatively controlling the arms 2, 2', in such a manner that either thereof shall operate in a plane common to the other, as in its movements in the direction of and away from each other, I provide an elongated independent yoke 7', said yoke, in this instance, being permanently fastened, as at the point 6'', to the arm 2', and surrounding and freely embracing the opposite arm 2. Hence, the arm 2, may be urged in the 20 direction of the arm 2', and permitted to recede therefrom without any appreciable deflection from the plane common to both of said arms.

7'' denotes an elongated keeper which, 25 in this instance, has its heel turned around the arm 2', rocks thereon accordingly, as at the point 6''', and underlies, at all times, the opposite arm 2, its free end-portion being turned upwardly for the formation, 30 within the plane of movement of, and beyond, the arm 2, of an upstanding stop substantially as shown in the drawing, and through the medium of which the distending action of the respective arms of the device, 35 each relatively to the other, is limited.

40 Keeper 7'' is elastically controlled, as through the medium of a controlling-spring 8, the latter, by preference, being in coiled form, encircling the arm 2' adjacent to the heel of the keeper aforesaid, and tending at all times to elastically rock such keeper upwardly into contact with the arm 2.

45 The keeper 7'' is constructed from metal in the form of a flat strip, and affords means whereby the arm which it underlies may be checked and held under various adjustments thereof relatively to the opposite arm of the device, such means, in this instance, consisting of a series of upstanding notches, 50 8', arranged longitudinally along said keeper at one side margin thereof, such side margin being upturned to this end, and the notches aforesaid being provided, each for the reception and occupancy of the arm, 55 as 2, accordingly as the same shall have been adjusted, at any time, relative to the opposite arm.

60 For limiting the reverse rocking action of the keeper 7'', and incidentally for strengthening the same, there may, when desired, be provided a stop-bar 9, the same primarily rising from the keeper 7'', at a point near its heel, thence turned in approximate parallelism therewith, overlying 65 the arm 2, and firmly engaging at its dis-

tant end the upturned distant end-portion aforesaid of said keeper, all as clearly indicated in the drawing.

In practically applying my improved lifter, the arms thereof being fully distended, or separated each from the other, the user duly adjusts the device to a plate, saucer, or the like, to be handled, and so that the same shall register marginally with the space intervening between the prongs of 75 each of the dish-grasping clips made use of, then urges or squeezes the arms of the device together, or either thereof in the direction of the other, thereby causing said clips to each straddle such dish, or the like, at 80 a point along its margin, the keeper aforesaid, under the stress of its controlling spring, automatically locking said arms, either thereof against retraction from the other; whereupon, by means of my improved 85 lifter, the dish, or the like, thus grasped thereby, may be readily handled, without the necessity of the user bringing his or her hand or hands into contact therewith, and as for the purpose of cleansing such dish, 90 or the like, or subjecting the same to any other desired treatment.

For freeing such dish, or the like, after the same shall have been treated as stated, it is only needful that the user depress the 95 keeper 7'', as by duly applying stress thereto at the free end-portion thereof, arms 2, 2' being permitted, accordingly, to spring apart, and said keeper, under the tendency of its controlling spring, returning to its 100 normal position, in readiness to again automatically lock the arms of the device against retraction, thereof either from the other, when the same shall have been again duly 105 adjusted for the handling of an additional 110 dish, or the like, to be cleansed or otherwise treated, as hereinbefore explained.

In some instances, as in the case of a deep article, such as a cuspidor, and by reason of the peculiarity of its general contour, the device may be advantageously availed of for the purposes hereinbefore set forth, even though each of the clips aforesaid affords only a single prong instead of dual prongs, 115 the latter being more serviceable and desirable in the handling of shallow dishes, as plates, saucers, and the like.

It will be seen that my improved dish lifter is well adapted for the purposes for which it is intended, insuring, as it does, 120 markedly sanitary conditions in the handling of the article or articles to be cleansed, or otherwise treated, and further that the same may be modified to a considerable extent without departure from the scope of 125 the claim hereto appended.

I claim:

A dish-lifter comprising a pair of connected, complementary arms held normally apart under spring-tension, formed from 130

wire, and affording, each a non-returned, 5 advance end-portion bowed away from the longitudinal center-line of the device and fitted with a plurality of dish-grasping elements; a flat keeper having its heel turned around one of the complementary arms aforesigned, for a rocking action upwardly thereon, and extending to and normally underlying the opposite complementary arm, 10 one longitudinal margin of said keeper being turned upwardly therefrom and provided at its top edge with a plurality of notches; a stop-bar supported by said keeper

and in conjunction therewith freely embracing the opposite complementary arm aforesigned and thereby limiting the rocking action on the part of such keeper; and an elastic element, the latter disposed to yieldingly urge said keeper, at all times and at some one of the notches aforesigned, upwardly into engagement with the complementary arm which it normally underlies. 15 20

ANGELO PANASCI.
